UNITED STATES PATENT OFFICE.

WALTER P. DORL, OF DETROIT, MICHIGAN, ASSIGNOR TO DORL-WILEY ONE LADY AUTO TOP COMPANY, A CORPORATION OF MICHIGAN.

VEHICLE-TOP.

1,162,042.

Specification of Letters Patent. Patented Nov. 30, 1915.

Application filed October 8, 1913. Serial No. 794,028.

To all whom it may concern:

Be it known that I, WALTER P. DORL, a citizen of the United States of America, residing at Detroit, in the county of Wayne and State of Michigan, have invented certain new and useful Improvements in Vehicle-Tops, of which the following is a specification, reference being had therein to the accompanying drawings.

10 This invention relates to vehicle tops and more particularly to tops for automobile bodies having two or more seats.

An object of the invention is to provide a top having a minimum number of supporting bows and so constructed that it may be extended or folded with facility by one person.

20 A further object is to provide a simple construction having certain other new and useful features all as hereinafter more fully described.

To these ends the invention consists in the matters hereinafter set forth and more particularly pointed out in the appended claims, 25 reference being had to the accompanying drawings in which—

Figure 1 is a longitudinal section through a top embodying the invention, showing the same in operative position upon an automobile body and with parts in side elevation; Fig. 2 is a side elevation of the frame of the same in folded position; Fig. 3 is a transverse section on the line $x-x$ of Fig. 1; Fig. 4 is a detail showing a portion of a rear seat 35 in plan view; and Fig. 5 is an enlarged sectional detail.

The frame of the top embodying this invention comprises a front supporting bow 1 which is pivotally attached at its end to suitable brackets 2 secured to the sides or arms 3 of the rear seat of the vehicle body, and a rear supporting bow 4 which spans the top and forms the rear end thereof, the ends or side arms of the bow extending downwardly 45 when the top is raised or in operative position, adjacent to the back stays 5 which are secured in the usual manner to the back bow at their upper ends and to the body or seat back at their lower ends.

50 A horizontally disposed bow 6 forms the front end of the top frame and extends over the upper end of the usual wind shield 7 of the vehicle when the top is up. The rear

ends of the bow 6 are connected to other parts of the frame in a manner hereinafter described by means of links 8 which are pivotally attached thereto at one end. An intermediate or supplemental bow 9 is pivotally connected to the side arms of the rear bow 4 by providing each arm with a longitudinal guide slot 10 to receive a stud 11 or other suitable projection on each of the ends of the bow, and the upper end of each slot is formed with an offset or lateral recess 12 to receive the stud when the top is up with said intermediate bow extending forwardly from the back supporting bow in a nearly horizontal position and hold the pivoted rear ends thereof in raised position. The intermediate portion of this bow 9 which spans the top, is held in position to give the desired shape to the cover, by means of braces 13 which are pivotally attached at their forward ends to the main bow 1 at each side of the top and at their rear ends these braces 15 are pivotally secured to said bow 9. Each brace 13 is formed of two parts which are connected by a downwardly breaking rule joint 14 or similar pivotal connection so that when the top is folded, the bow 9 after being 20 folded into substantial parallelism with the bow 4 by sliding its ends downward in the slots 10, will lie between the supporting bows with the main bow 1 near to and substantially parallel with it. The rear ends of the links 25 or connecting bars 8 are each preferably pivotally connected to one of the parts of each of these braces 13 and each link passes the bow 1 adjacent to its inner side through a suitable guide loop 15 on said bow to guide 30 the links in their movements and give rigidity to the forward part of the top. A second or supplemental bow 16 is provided between the main bow 1 and the forward end bow 6 to give the desired shape to the forward part 35 of the top and this bow is connected at each end to the main bow 1 intermediate the ends of the side arms thereof, by links 17 pivotally attached at one end to the rear ends of the bow 16 and at their opposite ends to 40 ears 18 on the forward edge of the main bow. The fabric cover 19 of the top is secured to the several bows so that it will be stretched 45 smoothly and evenly thereon when the top frame is extended and secured in extended 50 position by the usual stay straps 20 attached

to the front end bow 6 near the forward part thereof and detachably secured at their lower ends to the wind shield 7 or other suitable rigid anchorage. When the top is released by releasing the straps 20 the links 17 may be swung downwardly against the forward side of the bow 1 to lower the rear ends of the supplemental bow 16 and this bow is held in operative position when the 5 links are turned upwardly to the position shown in Fig. 1, by the tension put upon the cover 19 when the top is held by the stay straps. A pin 21 or other lateral projection is provided upon each side arm of the bow 16 in such a position that when said bow is swung upwardly by its links, said pins will engage beneath the curved connecting bars 8 and hold said bars against swinging downwardly. This locking of the bars 8 in operative position also locks by reason of their 10 pivotal connection with one of the members of each brace 13, said braces against breaking downwardly. The front bow 6 and supplemental bow 9 are therefore locked in operative position by throwing the links 17 upwardly to raise and lock the bow 16.

In order that the rear supporting bow 4 may fold rearwardly with the folding of the tops, into proper relation with the main bow 1, it is provided with rolls 22 on its lower ends to engage and move in suitable slots in guides 23 located adjacent to the upper edge of each arm 3 of the rear seat, said guides being curved forwardly and 15 downwardly to conform substantially to the curvature of the upper edge of said arms. If found desirable these guides 23 may be formed integral with the brackets 2 at their forward ends and connected at their rear ends by a rail 24 which is bent to conform 20 to the shape of the seat back near its upper edge and adapted to be bolted or otherwise firmly secured to said back. This rail is preferably provided with buttons 25 or other 25 suitable means for securing the back-stays and curtains to the seat back, and suitable downwardly extending rest-arms 26 may be formed integral with the guides or secured thereto to support the top when in folded 30 position. Each guide slot is formed at its upper or rear end with a notch 27 at its lower side into which the roller 22 will drop when the top is raised and in which it will be held by the strain put upon the 35 fabric cover by the stay straps 20 so that the ends of the rear bow will be prevented from sliding forwardly in their slots and the bow will be locked in an upright position.

Each roller 22 is attached to the end of 40 one of the side arms of the bow 4 by means of a shouldered bolt 28 upon which the roller is sleeved, said bolt being provided with a head at one end and a reduced and screwthreaded shank at its opposite end to 45 pass through an eye in the end of the bow.

A cap nut 29 on the outer end of the bolt secures the bolt in place and the head of the bolt and the slot in the guide 23 are covered by a suitable shield 30 secured to the inner side of the guide over the slot. Obviously the guides may be made integral 70 with the brackets 2 as shown, or separate therefrom and from each other, and attached to the seat in any suitable manner.

To fold the top, it is only necessary to detach the stay straps 20 from the wind shield, then turn the links 17 downwardly, thus unlocking the bars 8 and jointed stays 13. The bow 1 may then be swung rearwardly as when the strain is taken from the cover 80 by detaching the straps, the ends of the bow 9 will move forwardly out of the notches 12 and slide down the guide slot 10, and the rolls 22 will slip out of their notches 27 as soon as the back stays are slackened and 85 roll down the inclined guide slots in the guides 23, carrying the rear supporting bow forwardly. The folding of the top may thus be accomplished with ease and facility 90 by one person and may be as easily raised and secured in extended position.

The particular construction gives a very rigid frame with a minimum number of supporting bows to obstruct the view of the occupants of the vehicle. The front and intermediate bows which give the desired 95 shape to the top are so arranged that they are all concealed beneath the fabric cover and in no way obstruct the view or the exits or entrances to the vehicle.

Obviously changes may be made in the form and arrangement of parts without departing from the spirit of my invention and I do not therefore limit myself to the construction shown.

Having thus fully described my invention what I claim is:

1. In a vehicle top, the combination of a pivoted supporting bow, a second bow, guides adapted to be secured to a vehicle body for pivotally supporting and guiding the second bow, and a folding connection between said bows with an end of said connection movable longitudinally of said second bow.

2. In a vehicle top, the combination of a pair of pivoted bows, guides for the lower ends of one of the bows extending toward the other bows to guide said ends when the top is folded, and means slidably into parallelism with one of said bows adapted to permit one bow to be moved toward the other.

3. In a vehicle top, the combination of a main supporting bow pivoted at its lower end, a back bow, means pivotally supporting the lower end of the back bow and extending from adjacent to the rear end of the top forwardly toward the pivotal support of the main bow, and means including a bow 125

slidable into parallelism with said back bow adapted to coöperate with said bows in maintaining the top in a raised position.

4. In a vehicle top, the combination of a main bow, a back bow, back-stays secured to the back bow, means for holding the lower end of the back bow with said end adjacent to the lower end of the back-stays, said holding means being adapted to permit the movement of said lower end of the back bow forwardly toward the main bow when the top is folded, and means including a slidable bow and a two-part brace for holding said main and back bows in a raised position.

5. In a vehicle top, the combination of pivoted supporting bows, a supplemental bow between the supporting bows, means on one of the supporting bows to pivotally attach the ends of the supplemental bow thereto and guide said ends longitudinally thereof, a jointed brace pivotally connected at its ends to the other of said supporting bows and to the supplemental bow, and means pivotally connected to said brace and to one of said supporting bows for holding the forward end of the top when raised.

6. In a vehicle, the combination of a main bow pivotally supported at its lower end, a back bow, means for pivotally supporting the lower end of the back bow and guiding the same toward the pivoted lower end of the main bow, said back bow being provided with longitudinal guide slots, a supplemental bow guided at its end in said guide slots and extending forwardly toward the main bow, and a brace pivotally connected at its rear end to the supplemental bow and at its forward end to the main bow and provided with a downwardly breaking joint intermediate its ends.

7. In a vehicle top, the combination with a main bow, a horizontally disposed bow, connecting bars pivotally attached to the ends of the horizontal bow and having a sliding movement at the inner sides of said main bow, means movably supported by the rear side of said main bow for holding said bars, and an intermediate bow between the main and horizontal bows adapted to support said bars and horizontal bow in operative position.

8. In a vehicle top, the combination of a main bow, a horizontally disposed front end bow, connecting bars pivotally attached to the rear ends of the main bow and extending rearwardly of said main bow, means at the rear side of said main bow for movably supporting said bars relative to said main bow, an intermediate bow between the main and end bows, means connecting the ends of the intermediate bow to the main bow permitting an upward movement of the said

ends relative to the main bow, and means on the intermediate bow to prevent the end bow from turning downwardly at its rear end.

9. In a vehicle top, the combination of a main bow pivotally supported at its lower ends, a supplemental bow rearwardly of the main bow, downwardly movable supporting means for the supplemental bow, a front end bow, members connecting the rear ends of the end bow and said supporting means, an intermediate bow between the end and main bows, and means on the main bow for supporting the rear ends of the intermediate bow and adapted to raise and hold said intermediate bow into engagement with said members.

10. In a vehicle top, the combination of a main bow, a back bow, a supplemental bow having the rear ends thereof movable longitudinally of said back bow, means forming a pivotal connection between said supplemental bow and said main bow, guides adapted to be secured to the sides of a vehicle body and each having a longitudinal guide slot, and means on the lower ends of the back bow to engage said slots.

11. In a vehicle top, the combination of a main bow, a back bow, guides adapted to be secured to the sides of a vehicle body and each provided with a forwardly and downwardly curved guide slot having a lateral recess adjacent to its upper rear end, and rollers on the lower ends of said back bow to engage said slot and recess.

12. In a vehicle top, the combination of a main bow pivotally supported at its lower end, a back bow, a supplemental bow between the main and back bows, means connecting the ends of the supplemental bow with the back bow permitting a movement of said ends longitudinally of said back bow, brace members connecting said supplemental bow and the main bow and each having a downwardly breaking joint intermediate its ends, guide members adapted to be secured to the sides of a vehicle body rearwardly of the main bow and each formed with a guide slot, rolls on the lower ends of the back bow to engage said slots, a horizontally disposed front end bow, connecting members pivotally attached at one end to said brace members and at their opposite ends to the rear ends of said end bow, guides on the main bow for said connecting members, and means carried by the main bow for preventing the downward movement of said connecting members.

In testimony whereof I affix my signature in presence of two witnesses.

WALTER P. DORL.
